CLAIM

The ornamental design for headlight lens, as shown and described.

DESCRIPTION

FIG. 1 is an elevated front left perspective view showing a first embodiment of our new design, the broken line showing being for illustrative purposes only, and forms no part of the claimed design.

FIG. 2 is a front left view of the headlight lens design shown in FIG. 1.

FIG. 3 is a plan view of the headlight lens design of FIG. 1.

FIG. 4 is a left side view of the headlight lens design of FIG. 1.

FIG. 5 is a front view of the headlight lens design of FIG. 1.

FIG. 6 is a bottom view of the headlight lens design of FIG. 1.

FIG. 7 is an elevated front left perspective view showing a second embodiment of our new design, the broken line showing being for illustrative purposes only, and forms no part of the claimed design.

FIG. 8 is a front right view of the headlight lens design shown in FIG. 7.

FIG. 9 is a plan view of the headlight lens design of FIG. 7.

FIG. 10 is a right side view of the headlight lens design of FIG. 7.

FIG. 11 is a front view of the headlight lens design of FIG. 7; and,

FIG. 12 is a bottom view of the headlight lens design of FIG. 7.
